UNITED STATES PATENT OFFICE

BENJAMIN H. SMITH, OF NILES, MICHIGAN, ASSIGNOR TO MICHIGAN WIRE GOODS COMPANY, OF NILES, MICHIGAN

DISPLAY RECEPTACLE

Application filed March 28, 1932. Serial No. 601,601.

The main object of this invention is to provide a display receptacle having a plurality of compartments, certain of the compartments being adjustable to different capacities and the device also being adjustable to provide stepped shelving or a shelf and a receptacle.

A further object is to provide a structure having these advantages which may be compactly collapsed and is adapted for use in series for display purposes.

Objects pertaining to details and economies of my invention will appear from the description to follow. The invention is defined in the claims.

A structure embodying the features of my invention is illustrated in the accompanying drawings, in which:

Fig. 1 is an end view of my improved display receptacle.

Fig. 2 is a front view thereof.

Fig. 3 is a plan view.

Fig. 4 is a top or plan view with the receptacle collapsed.

Fig. 5 is a perspective view of one of the bottom members.

Fig. 6 is an end elevation of a modified form or embodiment of my invention.

Fig. 7 is a fragmentary front elevation of the embodiment shown in Fig. 6.

Fig. 8 is a vertical section of a plurality of my improved receptacles arranged in operative relation.

Fig. 9 is a vertical section of another assembly of my improved receptacles on a line corresponding to line 9—9 of Fig. 10.

Fig. 10 is a fragmentary transverse vertical section on line 10—10 of Fig. 9.

Fig. 11 is an enlarged fragmentary perspective view illustrating details of the connections between the assembled receptacles.

My improved receptacle comprises front members designated generally by the numeral 1, back members designated generally by the numeral 2 and stepped end members designated generally by the numeral 3. The end members 3 comprise front and rear uprights 4 and 5 and central uprights 6. Horizontal bottom bars 7 are fixedly secured to these uprights as is also the top horizontal bar 8.

This top horizontal bar is substantially one-half the length of the bottom horizontal bar and extends only to the central upright 6. The intermediate horizontal bar 9 extends from the rear upright to the upper end of the front upright 4. The vertical slats or wall members 10 terminate at the intermediate horizontal bar while the vertical slats or wall members 11 extend to the top bar 8.

The back member is made up of horizontal bars 12 having eyes 13 at their ends pivotally engaging the rear uprights 5 and vertical slats 14 fixedly secured to these bars 12.

The front member comprises the horizontal bar 15 having the vertical slats 16 secured thereto. The bars 15 have eyes 17 at their ends pivotally engaging the front uprights 4 of the end members.

I provide a partition member consisting of horizontal bars 18 and uprights 19, the horizontal bars having eyes 20 at their ends engaging the central uprights 6.

With the parts thus arranged they may be collapsed upon each other as shown in Fig. 4 and front and rear compartments are provided. The rear compartment is substantially twice the depth or capacity of the front compartment.

Each compartment is provided with a bottom 21 comprising longitudinal bars 22 having downturned ends 23 and slats 24. These downturned ends of the bottom members are selectively engageable with the horizontal bars of the end members, thus providing rear compartments of different capacities, or a rear compartment and a shelf when the front bottom member is engaged with the intermediate cross bar 9, or stepped shelves when both bottom members are adjusted at the top of the compartments.

The front and rear uprights of the end members are preferably extended into legs 25, the ends of which are bent upwardly and disposed in crossed relation providing braces 26.

In the modification shown in Figs. 6 and 7 the structure is the same as that described with the exception that the front legs are omitted and the rear legs 27 are of such length as to support the receptacle in upright

position with the end bars inclined as is illustrated, the purpose of this being to more effectively display the contents.

The units shown in Figs. 1 and 2 and the units shown in Figs. 6 and 7 are designed to be assembled in alignment with the units having the shorter legs supported between a pair of the other units. For this purpose, the units shown in Figs. 6 and 7 are provided with downwardly facing hooks 29 which may be engaged over the top bars 8 of a pair of the taller units or over the intermediate bars 9. When the hooks are engaged with the bars 9, the receptacles are supported in the same horizontal plane as shown in Fig. 8. When the hooks are engaged with the top bars 8 the intermediate receptacle is supported in an intermediate position relative to the other receptacles. In another assembly, the intermediate or lower units may be placed in front of the taller units thereby providing a structure which may be adjusted to meet the particular requirements or situation in the matter of space or goods to be displayed or the effect desired.

I have illustrated and described my improvements in an adaptation which has proved highly satisfactory for display purposes, and one which is adaptable for displaying a variety of goods. I have not attempted to illustrate the variations and adaptations of which it is capable.

Having thus described my invention what I claim as new and desire to secure by Letters Patent is:

1. A receptacle comprising a back and front members and stepped end members pivotally connected to permit collapsing thereof, the end members comprising top, bottom and intermediate horizontal bars and front, rear and central uprights, the top bars terminating at the central uprights, a partition pivotally connected at its ends to said central upright thereby providing front and rear compartments, the rear compartment being substantially twice the depth of the front compartment, and independently adjustable bottom members for said compartments selectively engageable with the end cross bars to vary the capacity of the rear compartment or to provide a receptacle and a shelf or stepped shelves.

2. A receptacle comprising a back and front members and stepped end members, the end members comprising top, bottom and intermediate horizontal bars and front, rear and central uprights, the top bars terminating at the central uprights, a partition connected at its ends to said central upright thereby providing front and rear compartments, the rear compartment being substantially twice the depth of the front compartment, and independently adjustable bottom members for said compartments selectively

engageable with the end cross bars to vary the capacity of the rear compartment or to provide a receptacle and a shelf or stepped shelves.

3. A receptacle comprising a back and front members and stepped end members pivotally connected to permit collapsing thereof, the end members comprising top, bottom and intermediate horizontal bars and front, rear and central uprights, the top bars terminating at the central uprights, a partition pivotally connected at its ends to said central upright thereby providing front and rear compartments, and an adjustable bottom member for the rear compartment.

4. A receptacle comprising a back and front members and stepped end members, the end members comprising top, bottom and intermediate horizontal bars and front, rear and central uprights, the top bars terminating at the central uprights, a partition connected at its ends to said central upright thereby providing front and rear compartments, and an adjustable bottom member for the rear compartment.

5. A receptacle assembly comprising a pair of end units and an intermediate unit, each of said units comprising stepped end members, the end members comprising top, bottom and intermediate horizontal bars, and front, rear and central uprights, the top bars terminating at the central uprights, a partition connected at its ends to said central uprights, thereby providing front and rear compartments, and adjustable bottom members for said compartments, said intermediate unit having laterally facing hooks on its intermediate horizontal bars selectively engageable with the horizontal bars of the said end units whereby said intermediate unit is adjustably supported on said end units.

6. A receptacle assembly comprising a pair of end units and an intermediate unit, each of said units comprising stepped end members, the end members comprising top, bottom and intermediate horizontal bars, and a partition connected at its ends to said central uprights, thereby providing front and rear compartments, said intermediate unit having laterally facing hooks on its intermediate horizontal bars selectively engageable with the horizontal bars of the said end units whereby said intermediate unit is adjustably supported on said end units.

7. A receptacle assembly comprising a pair of end units and an intermediate unit, each of said units comprising end members having top, bottom and intermediate horizontal bars, and front, rear and central uprights, the top bars terminating at the central uprights, and adjustable bottom members for said units, said intermediate unit having laterally facing hooks selectively engageable with the horizontal bars of the said

end units whereby said intermediate unit is adjustably supported on said end units.

8. A receptacle assembly comprising a pair of spaced end receptacle units and an intermediate receptacle unit, each of said units comprising end members having top, bottom and intermediate horizontal bars, said intermediate unit having laterally facing hooks selectively engageable with the horizontal bars of the said end units whereby said intermediate unit is adjustably supported on said end units and in suspended position therebetween.

9. A receptacle assembly comprising a pair of spaced end receptacle units and an intermediate receptacle unit, each of said units comprising end members having horizontal bars, said intermediate unit having laterally facing hooks on its intermediate horizontal bars engageable with the horizontal bars of the said end units whereby said intermediate unit is supported on said end units and in suspended position therebetween.

In witness whereof I have hereunto set my hand.

BENJAMIN H. SMITH.
